UNITED STATES PATENT OFFICE.

BENTON C. ROWELL, OF CHICAGO, ILLINOIS, ASSIGNOR TO ANCHOR BRAKE SHOE AND MANUFACTURING COMPANY, OF CHICAGO, ILLINOIS, A CORPORATION OF ILLINOIS.

BRAKE-SHOE

1,187,467.

Specification of Letters Patent. Patented June 13, 1916.

Application filed January 2, 1915. Serial No. 51.

To all whom it may concern:

Be it known that I, BENTON C. ROWELL, a citizen of the United States, and a resident of Chicago, in the State of Illinois, have invented certain new and useful Improvements in Brake-Shoes, of which the following is a specification.

My present invention relates to wearing brakes or shoes such as are commonly used 10 on railway rolling stock, and more particularly to brake shoes for this purpose which contain wear resisting inserts of different metal than the body of the shoe.

The principal objects of my present invention are the provision of reinforcements 15 for the body of the shoe which shall give maximum strength to all parts of the shoe; the provision of reinforcing members which are adapted to protect the corners or upper 20 edges of the shoe from external injury; the provision of improved means for attaching the supporting strap or lug of the shoe to the reinforcing members; the provision of means for attaching wearing inserts to 25 the reinforcing members of the shoe; the provision of improved means for anchoring the wearing inserts in the body of the shoe and generally to improve, cheapen and simplify the construction of brake shoes for 30 railway or other vehicles together with such further objects as will hereinafter appear.

In attaining the foregoing objects and certain additional advantages to be below disclosed I have provided the construction 35 illustrated in the accompanying drawings, wherein:-

Figure 1 is a plan view of the improved brake shoe as a whole; Fig. 2 is a section of the improved brake shoe on plane 5—5 40 of Fig. 1 with the body portion of the brake shoe omitted to show more clearly the arrangement of the reinforcement and the wear resisting inserts attached thereto; Fig. 3 is a section on the plane 3—3 of Fig. 2 with 45 the body portion of the brake shoe shown in position; Fig. 4 is a section on the plane 4—4 of Fig. 2 showing the relation between the wear resisting inserts, the reinforcement, and the body portion of the shoe; Fig. 5 is a section on the plane 5—5 of Fig. 50 1; Fig. 6 is a section on the plane 6—6 of Fig. 2 showing the body portion in position; Fig. 7 is a side elevation of one of the two reinforcing members; Fig. 8 is a section 55 through the supporting strap of a modified

form of brake shoe specially adapted for use in connection with flanged wheels; Fig. 9 is a side elevation of the form of brake shoe shown in section in Fig. 8; Fig. 10 is a plan view of a modified form of brake 60 shoe; Fig. 11 is a section of the brake shoe shown in Fig. 10 on the plane 11—11; and Fig. 12 is a section of the brake shoe shown in Fig. 11 on the plane 12—12.

In the drawings are illustrated by way of example three forms of brake shoe, constructed in accordance with my present invention.

Reference will now be made to Figs. 1 to 7 which illustrate the first of these forms. 70 The particular form of reinforcement used will be described first. This reinforcement preferably consists as shown of two angular members 10 arranged on either side of the brake shoe at the upper side thereof, 75 so as to inclose the two upper corners or edges of the brake shoe. The vertical parts 11 of these reinforcing members are continuous throughout the whole length of the brake shoe, with the exception of counter-sunk apertures 12 arranged therein to facilitate the anchoring of the metal inserts in the brake shoe. The upper or horizontal portions of the reinforcing members are, however, arranged with dove-tailed recesses or 80 cut-away parts 13 to provide interlocking means between the body of the brake shoe and the reinforcement.

At the center of each reinforcing member is formed a projecting part 14 adapted 90 to act as an anchor or support to the bar 15 by which the brake shoe is attached to its supporting apparatus.

The substantially U-shaped wearing inserts 16 are attached to the reinforcing members in the manner illustrated in Fig. 4. The apertures 12 in the vertical parts 11 of the reinforcing members are countersunk on their outer sides so that when the inserts are cast in position between the two 100 reinforcing members, the metal which flows into the aperture 12 dovetails with the reinforcing members so as to form anchors for the insert.

The body portion 40 of the brake shoe is held in place, not only by the wearing inserts as illustrated in Figs. 4 and 5, but also by means of the ribbed parts 1 arranged on the inner walls of the vertical sides 11 of the reinforcing members. 110

In the form of the invention illustrated in Figs. 10 to 12 no wearing inserts are employed, the brake shoe body being attached directly to the reinforcements, by 5 means of counter-sunk apertures 41 preferably arranged on the upper surface of the reinforcements. The body of the brake shoe is cast *in situ* with the reinforcing members arranged so that they will lie along the upper 10 and outer corners of the brake shoe when the latter is formed. During the casting operation the metal of the shoe body enters the counter-sunk apertures and forms a dove-tail connection between the shoe body 15 and the reinforcing members.

With regard to the form of construction shown in Figs. 8 and 9, attention is called to the fact that as the brake shoe is adapted particularly for use in connection with 20 flanged wheels and is arranged so that the shoe overlies and extends beyond the flange of the wheel, the supporting strap 35 is arranged at one side of the brake shoe as a whole in order to be vertically over the part 25 where the greatest resistance is encountered. This fact involves a somewhat peculiar form of construction for the supporting strap. Preferably as illustrated, the strap is connected to the reinforcing members 36 30 and 19 at each end. In this form of construction, as in the first form previously described, one reinforcing bar 19 is preferably used in such a way that it protects the corner of the brake shoe from injury, 35 while a rib or flange 37 projecting into the material of the shoe provides the necessary resistance to vertical movement which is required by the supporting strap connected thereto. Accordingly, a channeled iron re- 40 inforcing member 19 is preferably used with one of its flanges 38 arranged externally with respect to the upper surface of the brake shoe, while the other flange extends substantially horizontally into the body of 45 the shoe. The other reinforcing member 36 is, however, arranged with its flanges vertically arranged to provide a suitable support for the other end of the strap 35 which is formed with a head 40^a for engagement 50 therewith.

The externally arranged channeled member 19 is secured to the body portion of the brake shoe not only by means of its inwardly projecting flange, but also by means of an 55 anchor 20 having a head 21 adapted to engage the channeled member 19. The other end of the anchor 20 is provided with a hooked portion 22 which is embedded securely in the metal of the shoe.

Having thus described my invention and illustrated its use what I claim as new and I desire to secure by Letters Patent:

1. A brake shoe for flanged wheels comprising in combination a body portion 60 adapted to overlie the flange, a reinforcing

member in said body portion above the groove for the said flange and a second reinforcing member at the outer vertical face of said body portion.

2. A brake shoe for flanged wheels comprising in combination, a body portion, a reinforcing member in said body portion above the groove for the said flange, and a second reinforcing member externally arranged at the outer and upper corner of the 75 said body portion.

3. A brake shoe comprising a body portion and a metallic channeled reinforcing member embedded in said body portion, a second metallic channeled reinforcing member embedded in said body portion having its flanges angularly arranged relatively to the flanges of the first member.

4. A brake shoe comprising in combination, a body portion, a reinforcing member embedded therein having a vertical portion with a series of apertures formed therein, and anchoring members adapted to be passed through said apertures and embedded in 80 said body portion.

5. A brake shoe comprising in combination, a body portion, a metallic channeled reinforcing member having a series of apertures formed therein, anchoring members adapted to be passed through said apertures, 85 heads on said anchoring members adapted to engage and hold the said reinforcing members and hooked ends on said anchoring members adapted to be embedded in said body portion.

6. A brake shoe comprising a body portion, an angular reinforcing member adapted to protect externally one corner of said brake shoe, and means for attaching said reinforcing member to said body portion. 100

7. A brake shoe comprising a body portion, an angular reinforcing member adapted to protect externally one corner of the said body portion and a flange on the said reinforcing member projecting into and embedded in said body portion.

8. A brake shoe comprising, in combination, a body portion, an angular reinforcing member adapted to protect externally an upper edge of said body portion, and means for attaching the vertical portion of said member to the body portion.

9. A brake shoe comprising, in combination, a body portion, an externally arranged angular reinforcing member on one side of 110 said body portion having an upper substantially horizontal portion and a supporting member having one end arranged under said horizontal portion.

10. A flanged brake shoe comprising in combination, a body having a flange portion, a strengthening insert in said body portion, a strengthening insert in said flange portion, and an attaching lug engaging both of said strengthening inserts. 115

11. A brake shoe comprising in combination a body portion, angular reinforcing members adapted to protect externally the upper edges of the said body portion, and 5 means for connecting the vertical portions of the said reinforcing members.

In testimony whereof I have hereunto

signed my name in the presence of the two
subscribed witnesses.

BENTON C. ROWELL.
